TERMINAL CLIP

Filed Nov. 27, 1939

UNITED STATES PATENT OFFICE

2,253,417

TERMINAL CLIP

William C. Clark, Urbana, Ill.

Application November 27, 1939, Serial No. 306,363

1 Claim. (Cl. 294—92)

The present invention is an improvement in terminal clips for use with battery lifting straps.

The principal object of the present invention is to provide a terminal clip which can be formed from one piece of metallic plate and which will, in operation, firmly encompass and grip a battery terminal.

Another important object of the present invention is to provide an economically produced terminal clip which will firmly grasp a battery terminal regardless of the surface condition thereof and in such a manner as to prevent their disconnection until the same is desirable, at which time, the clip can be disconnected from the terminal in a simple manner.

Other objects of the present invention will be in part obvious and in part pointed out in the following detailed description of the accompanying drawing which discloses one manner in which the present invention can be carried out, whereby, those persons skilled in the present art can readily apprehend and reconstruct the invention.

In the drawing:

Fig. 1 is a perspective view of a battery having a battery lifting strap using terminal clips according to the present invention connected to the terminals of the battery.

Fig. 2 is a side elevation of the present terminal clip connected to a battery terminal.

Fig. 3 is a top elevation of Fig. 2.

Fig. 4 is a side detail cross sectional view taken on line 4—4 of Fig. 3, and

Fig. 5 is a side detail cross sectional view of the terminal clip according to the present invention.

Referring now more particularly to the accompanying drawing wherein like and corresponding parts are designated by similar reference characters, numeral 1 generally indicates a wet cell storage battery having positive and negative terminals 2 and 3.

A battery lifting strap 4 of the flexible or semi-flexible type is connected at each end thereof to a terminal clip 7 by means of a metal band 5 passing through a slot 6 formed in the clip 7 and connected by rivets, or the like, to an end of the strap 4.

The terminal clip 7, which can be formed if desired from a single piece of plate material by a single stamping operation, has, in addition to aforementioned slot 6, a tongue 8 cut and bent upwardly from the medial portion thereof. The outer end portion 9 of tongue 8 is bent to extend substantially horizontal with or downwardly towards the body 7 of the clip.

The end face 11 of tongue 8 is curved as is the

side end wall 12 formed in the clip 7. Said end 11 and said end wall 12, together form the major portion of a circle having a diameter somewhat equivalent to the diameter of a battery terminal. End 11 tapers inwardly relative to the end portion 9 of tongue 8, whereby the upper edge of end 11 forms a knife edge 10.

Clip 7 is bent upwardly and outwardly as at 13, which in turn forms a lifting handle 14, which handle 14 is sufficiently large for at least one finger to fit thereunder and lift that end of clip 7 upwardly.

A battery lifting strap 4, having a pair of clips 1 connected to the opposite ends thereof, is positioned diagonally across the battery 1, whereby, the opening formed by end 11 and wall 12 of the clips 7 may be placed with one of the battery terminals 2 or 3 therethrough and with end 11 and wall 12 encompassing the battery terminal. Upon strap 4 being pulled upwardly for lifting the battery 1, knife edge 10 will be caused to bite inwardly and downwardly into the terminal, due to the upward movement of strap 4 and its connection to clips 7. At the same time, the lower edge of wall 12 will bite into the terminal and will thereby cooperate with knife edge 10 in firmly gripping the terminal in such a manner that downward movement of the terminal relative to the clips 7 is prohibited. Knife edge 10

30 performs the function of a pivot for the terminal clip with the pressure being applied upwardly at one end by the lifting of the strap 4, thereby giving considerable leverage to the movement of wall 12 towards and into the battery terminal.

35 When it is desired to remove the battery lifting strap with its terminal clips from the battery 1, a sufficient pressure is applied to handle 14 which will lift wall 12 from the terminal, using knife edge 10 as the pivot point, and as handle 14 is

40 further moved upwardly, end 11 will contact the periphery of the terminal, withdrawing knife edge 10 from its position within the surface of the battery terminal. By having knife edge 10 and the lower edge of wall 12 upon different planes,

45 the one acts as a pivot for the other during the lifting movement of strap 4, thereby, through the medium of leverage, creating a greater force to the biting action of these edges, whereby, a firmer gripping of the battery terminal is provided.

50 Other types of handles than that shown can be readily connected to clips 7 and also an operative battery lifting device can be provided using a handle with but one clip 7 connected thereto, or only one clip 7 of the pair as shown can be used

where, for example, a battery terminal 2 or 3 has been destroyed. Clip 7 will grip a single terminal in such a manner that the battery can be readily lifted without the aid of the second clip.

The present invention is readily capable of being modified from the particular clip shown in the drawing, as for example, by changing the configuration of the tongue 8 and/or position of the knife edge 10. However, any such modifications thereof as come within the scope of the appended claim, I deem to be a part of my invention.

I claim:

A battery carrying strap having clips for engaging the truncated cone-shaped terminals of an electric storage battery, each clip comprising in combination a single strip of metal of a substantially rectangular configuration and having a slot formed in one end thereof whereby one end of the strap may be connected to each clip, each clip having an elongated opening formed therein with a rounded end wall, a tongue struck from

each metal strip having a contiguous connection therewith at a point opposite from the rounded end wall formed by the opening therein, the free end portion of said tongue lying in a plane above and parallel with the metal strip, the extremity of the free end portion of said tongue terminating in a rounded knife edge, which latter when combined with the rounded end wall of the opening formed within each metal strip provides a circular opening of a diameter capable of receiving one of the truncated cone-shaped terminals of the battery, a reduced projection formed contiguous with and extending from the opposite end of each of said clips, each projection extending upwardly and outwardly from the clip therefore, the outer extremity of each projection being remotely positioned with respect to its clip and providing handles whereby the clips may be lifted from the terminal post of the battery seated within the openings thereof when removing the strap.

WILLIAM C. CLARK.
